UNITED STATES PATENT OFFICE.

WILLIAM DAYTON FREDRICK AND WARREN E. GLASPEY, OF BRIDGETON, NEW JERSEY,
ASSIGNORS TO MILLVILLE MACHINE COMPANY, OF MILLVILLE, NEW JERSEY, A
CORPORATION OF NEW JERSEY.

VIAL-BOTTOMING MACHINE.

1,322,779.

Specification of Letters Patent. Patented Nov. 25, 1919.

Application filed November 23, 1914. Serial No. 873,609. Renewed October 26, 1916. Serial No. 127,967.

To all whom it may concern:

Be it known that we, WILLIAM DAYTON FREDRICK and WARREN E. GLASPEY, citizens of the United States, and residents of 5 Bridgeton, New Jersey, have invented certain Improvements in Vial-Bottoming Machines, of which the following is a specification.

Our invention relates to the manufacture 10 of small glass bottles or, as they are termed in the trade, "vials". As is well known, these bottles or vials are made from previously formed glass tubes which are cut into sections of the proper length, which sections are subsequently acted upon by suitable means, including the heating of the glass, for the purpose of forming the necessary necks, and also to provide or form 15 the bottoms.

20 The general practice heretofore has been to perform these operations by hand; suitable means being provided in the shape of jet flames to heat the ends of the tubes to an extent sufficient to soften the glass 25 whereby the necks and mouths, and bottoms could be formed.

This present invention relates to a machine adapted to perform automatically the 30 operation of bottoming tubes of glass which have had the neck and mouth portions previously formed therein.

While the present machine has been especially designed for the purpose of bottoming tubular sections comprising a double 35 blank having the mouth and neck portions at each end, and which are prepared or produced by the use of a machine forming the subject of a companion application, filed Nov. 23, 1914, Serial No. 873,610, it will be 40 understood that the present machine is capable of operating upon previously formed double blank tubular sections, no matter how the same have been produced, and irrespective of any mouth and neck portions 45 possessed by such sections, inasmuch as there are many vials on the market which do not possess the finished neck and mouth, but are of the same diameter throughout.

These and other features of our invention 50 are more fully described hereinafter, reference being had to the accompanying drawings, in which:

Figure 1, is a plan view of a machine de-

signed for bottoming vials made in accordance with our invention;

55

Fig. 2, is a front elevation of the same, partly in section on the line 2—2, Fig. 3;

Fig. 3 is an end elevation, partly in section on the line 3—3, Fig. 1;

Fig. 4, is a sectional view of a bottom 60 forming die which may be employed;

Fig. 5, is a detached view illustrating the method of feeding blanks to the supporting rolls;

Fig. 6, is a front elevation of the structure shown in Fig. 5;

Figs. 7, 8, 9, 10, 11 and 12, are diagrammatic views illustrating the manner of separating the blank into two sections and bottoming the separate sections of the same, 70 and

Fig. 13, is an end elevation of the structure shown in Fig. 12, showing the manner of discharging the finished vials.

1 is the bed plate of the machine, carrying brackets 2 at one end of the same having bearings 3 in which a main driving shaft 4 is journaled. This shaft may be driven by a pulley 5 to which motion is imparted in any suitable manner, and splined 80 to said shaft 4 is an adjustable friction pinion 6 whereby motion of said shaft may be imparted to a friction disk 7, mounted on the end of a short shaft 8 journaled in a suitable bearing 9. To effect adjustment of 85 the friction pinion on the shaft 4, in order to effect changes in the speed of motion transmitted, a screw shaft 10 may be arranged parallel to said shaft 4 and provided with a nut 11 having a yoke arm 12 for operative engagement with a hub 13 carried by the friction pinion 6.

Keyed to the shaft 8 is a pinion 14 which moves therewith when the friction disk is driven, and this pinion meshes with and drives a gear 15 mounted on the end of a counter-shaft 16 extending the length of the machine and journaled in suitable bearings 17. This counter-shaft 16 carries pinions 18 and 19 for a purpose to be described. 100 Paralleling the counter-shaft 16 is a second counter-shaft 20 journaled in suitable bearings 20^a and having a pinion 21 meshing with the pinion 18 of the counter-shaft 16 whereby shaft 20 may be driven. The shaft 105 20 carries bevel pinions 22 and 23 at its

ends, which bevel pinions are in mesh with and drive bevel pinions 24 and 25 carried by short vertical shafts 24^a and 25^a, suitably journaled and connected to and driving cams 26 and 27, for a purpose to be described.

Paralleling the counter-shafts 16 and 20 is a third counter-shaft 28, driven from the shaft 16 by pinions 19 and 29, respectively.

- 10 In addition to the bevel pinions 22 and 23, the shaft 20 carries a gear wheel 30 which meshes with and drives a pinion 31 carried by a short shaft 32 mounted in a bearing 33. The shaft 28 is journaled in bearings 35, and 15 carries at its end opposite the gear 29, a bevel pinion 36 which meshes with and drives a bevel pinion 37 mounted on a short shaft 38 in the same plane as the shaft 28 but at right angles thereto. The shaft 38 20 carries a pinion 39 which meshes with and drives pinions 40 and 41 mounted on short shafts 40^a and 41^a, which shafts carry at their outer ends cams 42 and 43, for a purpose to be described.

25 The gear 29 meshes with and drives a gear 45 on a shaft 46 journaled in bearings 47 carried by a supplemental table 1^a, mounted above the bed-plate 1, and said shaft 46 has another gear wheel 48 which meshes with 30 and drives a pinion 49 on the end of a shaft 50 paralleling said shaft 46 and journaled in bearings 47^a formed in extensions of the bearings 47. The supplemental table 1^a may be carried by pedestals 51 secured to the bed- 35 plate 1 of the machine, and the mechanism supporting the tubular sections of glass and the means operating thereon are carried above said supplemental table.

At one side of said table we provide a runway

- 40 way 55 to receive the tubular sections or blanks which, in the present instance, are double, each end forming the mouth of a finished vial or bottle, and these sections will be hereinafter referred to as "blanks." This 45 runway is carried by the supplemental table 1^a, and is inclined; the said blanks placed thereon coming to rest in engagement with the upper end of a vertically movable member 60, and on the upward movement of this 50 member said blanks will be elevated and delivered to the upper, inclined edges 61 of standards 62 whereby said blanks may be fed to sets or series of rollers 63, 63^a and 64, 64^a; being subsequently engaged by upper 55 rubber-faced rollers 65 and 66; the ends of said blanks being engaged by rotatable disks 67 and 68 in axial alinement therewith and carried by adjustable stems 67^a and 68^a mounted in tubular bearings 67^b and 68^b. 60 These several rollers and disks rotate in a manner hereinafter set forth. For the purpose of operating the elevating member 60, the following means may be provided:

The lower end of said elevating member 60 is connected by means of a link 70 with

a lever 71 pivoted at 72 to a post 73 carried by the bed plate 1, while the pinion 31 mounted on the end of the shaft 32 performs the function of a face-plate; said pinion carrying a pin 74 adapted to work in a slot 75 formed in said lever 71, and for every revolution of said pinion, the elevating member 60 will be raised and lowered. In the upward movement of said elevating member, a blank will be raised into position for 75 engagement by the several bottom rollers 63, 63^a, 64, 64^a, and the rubber-faced top rollers 65 and 66.

Paralleling the shaft 50 are a pair of short shafts 65^a and 66^a which carry the rubber-faced rollers 65 and 66. These shafts are carried by the ends of bell-crank levers 76 and 77, pivotally mounted on the shaft 50; the lower ends of said bell-crank levers being bifurcated as shown at 76^a and 77^a 85 and carrying between such bifurcated ends rollers 78 and 79 for engagement by cams 80 and 81 fixed to the shaft 46 and rotating with it. Upon rotation of said shaft 46, said cams come into contact with said rollers 78 90 and 79 and rock the bell-crank levers on the shaft 50, thereby raising the shafts 65^a and 66^a and with them the rollers 65 and 66. This action is timed to take place as the blanks are fed from the standards 62 to the 95 operative position, and after they come to rest upon the rollers 63, 63^a, 64, and 64^a, the rollers 65 and 66 descend into contact with the same upon the release of the bell-crank levers 76 and 77 by the continued rotation 100 of the shaft 46. The shafts 65^a and 66^a carry pinions 82 and 83 which mesh with and are driven by pinions 82^a and 83^a carried by the shaft 50.

Adapted to slides 85 and 86 carried by the 105 supplemental table 1^a are brackets 87 and 88, having arms 89 and 90 disposed substantially at right angles thereto, and these arms are slotted for the reception of vertically movable plates 91 and 92 which support the 110 rollers 63, 63^a, 64, and 64^a, respectively. These plates 91 and 92 are preferably in two pieces, adjustable with respect to each other for different sized blanks, and confined in their adjusted positions by any suitable fastening means such as the stud bolt shown. The lower ends of these plates carry rollers 93 and 94 which rest upon a movable platen 95 in contact with the cams 42 and 43 before referred to; being held in engagement with 120 said cams by means of springs 96, disposed below said platen and interposed between the table 1^a and the ends of the stems 97 carrying the same. These cams 42 and 43 are provided with flat faces 42^b and 43^b, and when 125 the shafts 40^a and 41^a respectively, carrying said cams are turned to bring said faces adjacent this platen, the latter is lowered by the springs 96, permitting the rollers 63, 63^a, 64 and 64^a to drop, and releasing the fin- 130

ished vials which fall onto a runway provided by a series of curved plates 98, from which they pass to inclined rails 98^a for discharge from the machine.

- 5 After the tubular sections of glass have been positioned by the several rollers 63, 63^a, 64, and 64^a so far as horizontal alinement is concerned, they are to be centered with respect to the disks 67 and 68. The stems 67^a and 68^a carrying said disks are mounted in bearings 67^b and 68^b carried by the slidable brackets 87 and 88 which are under the control of the cams 26 and 27; the latter being grooved at 26^a and 27^a for the reception of rollers 26^b and 27^b, carried by bars 99 and 100 slidably mounted in suitable guideways 99^a and 100^a on the under side of the supplemental table 1^a. These bars are slotted for the passage of the cam shafts 24^a and 25^a and 20 extend beyond the ends of said supplemental table 1^a; being connected at their outer ends to bars 101 and 102 operatively mounted on top of said table 1^a by means of studs 103 and 104; said bars 101 and 102 being connected at 25 101^a and 102^a to the bottom portions of the sliding members 87 and 88.

The bars 99 and 100 carry the rollers 26^b and 27^b adapted to the cam grooves 26^a and 27^a of the cams 26 and 27, and upon rotation of said cams the sliding members 87 and 88 are reciprocated and with them the several rollers 63, 63^a, 64 and 64^a, and the upper rubber-faced rollers 65 and 66; the said slidable members 87 and 88 having arms 105 and 106 35 with hubs 105^a and 106^a slidable on the shaft 50, and between said hubs 105^a and 106^a the hubs 76^b and 77^b of the bell-crank levers 76 and 77 are mounted so as to be movable by the hubs 105^a and 106^a. As the blanks are 40 only in frictional engagement with the several rollers, the surfaces of said rubber-faced rollers are beveled so that the rotative movement of the same during their outward movement will effect proper relative movement 45 of the ends of the blank as the center of the same is softened by heat.

In order that the blanks which are designed to form two bottles or vials may be separated into two sections, the central or 50 mid portion of the same must be heated so as to soften the glass, and during this heating operation the slidable members 87 and 88 are moved outward so as to cause said central portion of the tubular sections to collapse under the heating action. This movement is effected by the cams 26 and 27 with the aid of the mechanism described, and in order to effect the desired heating, jets of flame are directed against the central portion 55 of said sections from a series of burners 110, 111 and 112. These burners may be of the ordinary Bunsen type with the flame in the form of an elongated jet with its ends impinging on the glass. The movement of the 60 cams in effecting the lengthening operation

with respect to the central portion of these sections is gradual at first, but these cams have abrupt changes in their grooves so that when nearing the end of the elongating movement, such movement can be accelerated 70 with the result of attenuating the glass to such an extent as to close the central bore and when this occurs the flame is of such an intensity as to sever the thin connection and separate the original blank into two 75 parts with closed bottom ends.

Following this action the elongated ends of the separate sections which are substantially conical in shape require to be flattened to form the desired bottoms of the respective vials. For this purpose, a bottom die or anvil is brought into axial alinement with the two sections. This die, shown at 115 in Fig. 4, comprises a hub 116 carried by an arm 117 pivotally mounted on a post 118 80 carried by the supplemental frame 1^a; said hub receiving a spring 119 serving to press outwardly ends 120 which are designed to contact with the sections and form the bottoms thereof. The opposite end 121 of said 85 arm lies in the path of a cam 122 mounted on and rotating with the shaft 46. As soon as the blank has been severed, this bottom forming die is thrown up into place, and then the cams 26 and 27 have started to push 90 the slidable members 87 and 88 inward, forcing the ends of the separate sections of said blank into contact with the ends 120 of said die while said sections are rotating, and when such inward movement is complete, 100 these sections will be finally bottomed. Following this action the slidable members 87 and 88 will be moved outward by the cams 26 and 27 in the manner above described; the several rollers 63, 63^a, 64 and 64^a will be 105 lowered, and the finished vials will discharge onto the segments 98.

We claim:

1. In a machine for bottoming vials, the combination of a plurality of sets of horizontally disposed vial blank supports, means for heating the mid portion of the blank, means for longitudinally moving said sets of vial blank supports away from each other as the blank is heated to effect separation of the same into two sections, bottom forming means comprising plates for axial alinement with the blank sections and cushioning means between said plates, a pivoted carrier therefor, and means for actuating said carrier to bring said bottom forming means into axial alinement with said sections after separation thereof.

2. In a machine for bottoming vials, the combination of a plurality of sets of rotatable rollers forming vial blank supports, means for rotating the rollers of each set, means for effecting longitudinal movement of said sets of rollers with respect to each other, a feed trough, and a vertically mov- 125

- able elevator for lifting blanks from the feed trough to the sets of rotating rollers.
3. In a machine for bottoming vials, the combination of a plurality of separate and independently operable rollers forming a vial blank support, means for rotating the several rollers, a feed trough, means for elevating said blank from the feed trough to the rollers, and means for moving said rollers longitudinally with respect to the axis of the blank.
4. In a machine for bottoming vials, the combination of a plurality of sets of separate and independently operable rollers forming a vial blank support, means for rotating the several sets of rollers, a feed trough, means for elevating said blank from the feed trough to the rollers, and means for moving said sets of rollers toward and from each other and longitudinally with respect to the axis of the blank.
5. In a machine for bottoming vials, the combination of rotating roller supports, a pair of top rollers, hinged supports for said top rollers, cams for actuating said supports whereby the rollers may be moved onto and from the blanks, and means for effecting lateral movement of said rollers as they are rotated.
6. In a machine for bottoming vials, the combination of rotating roller supports, a pair of top rollers, hinged supports for said top rollers, cams for actuating said supports whereby the rollers may be moved onto and from the blanks, brackets supporting the lower rollers, sliding members carrying said brackets, and cams for actuating said sliding members to effect lateral movement of said rollers as they are rotated.
7. In a machine for bottoming vials, the combination of rotating roller supports, a pair of top rollers, hinged supports for said top rollers, guiding means for said supports, cams for actuating said supports to move the rollers onto and from the blanks, sliding members carrying said guiding means, and means for reciprocating said sliding members to effect lateral movement of top rollers.
8. The combination, in a machine for bottoming vials, of independent sets of horizontally disposed rotating vial blank supports, independent laterally movable members carrying the same, means for reciprocating said members with respect to each other longitudinally of the axes of rotation of said blank supports, and means for effecting rotation of the supports simultaneously with such reciprocative movement.
9. The combination, in a machine for bottoming vials, of independent sets of horizontally disposed rotating vial blank supports, independent laterally movable members carrying the same, means for reciprocating said members with respect to each other longitudinally of the axes of rotation of said blank supports, means for effecting rotation of the supports simultaneously with such reciprocative movement, and means for separating the blanks into two sections as their ends are moved outwardly.
10. The combination, in a machine for bottoming vials, of a rotating blank support, means for directing flame jets to heat the central portion of the blank, means for moving the blank supports to stretch said blank and separate the same into two sections as it is heated, bottom forming means for axial alinement with the previously heated ends of said sections comprising plates to engage the sections and a cushion spring between said plates, a swinging carrier for said bottom forming means, and means for actuating said carrier to bring said bottom forming means into alinement with the ends of said sections.
11. The combination, in a machine for bottoming vials, of independent sets of rotating blank supports, means for directing flame jets to heat the central portion of the blank, means for moving the sets of blank supports to stretch said blank and separate the same into two sections as it is heated, a bottom-forming die having cushioned bottoming members for engagement with said sections, a swinging carrier for said die, and means for actuating said carrier to bring the cushioned bottoming members of said die into axial alinement with the ends of said sections.
12. The combination, in a machine for bottoming vials, of a rotating blank support, means for directing flame jets to heat the central portion of the blank, means for moving the blank supports longitudinally with respect to the axis of the blank, the movement in one direction stretching said blank and separating the same into two sections as it is heated, and a die for axial alinement with said sections.
13. The combination, in a machine for bottoming vials, of a rotating blank support, means for directing flame jets to heat the central portion of the blank, means for moving the blank supports longitudinally with respect to the axis of the blank, the movement in one direction stretching said blank and separating the same into two sections as it is heated, a die for axial alinement with said sections, a pair of bottoming members carried by said die for engagement with the sections upon the return movement of the blank supports, and means for moving said die.
14. The combination, in a machine for bottoming vials, of sets of rotating blank supports, means for directing flame jets to heat the central portion of the blank, means for longitudinally moving said sets of blank supports, the movement in one direction serving to stretch said blank and separate

- the same into two sections as it is heated, while movement in the opposite direction is for a bottoming operation, a die for axial alinement with the bottom ends of said sections while they are separated, a swinging carrier for said die, means for actuating said carrier to bring said die into axial alinement with the bottom ends of said sections, a pair of bottoming members carried by said die for engagement with the sections as they are moved by the sets of blank supports, and a spring interposed between said bottoming members.
15. The combination, in a machine for bottoming vials, of independent sets of rotating blank supports, laterally moving members supporting the several sets, cams for moving said members toward and from each other, and means for operating said cams.
16. The combination, in a machine for bottoming vials, of a rotating blank support, supporting means for the same, a substantially horizontal movable platen upon which said supporting means rest, and rotatable cams in engagement with the under side of said platen, said cams serving to hold the platen normally in the elevated position and provided with flattened faces permitting lowering of the platen at intervals.
17. The combination, in a machine for bottoming vials, of a rotating blank support, supporting means for the same, a substantially horizontal movable platen upon which said supporting means rest, and rotatable cams in engagement with the under side of said platen, said cams serving to hold the platen normally in the elevated position and provided with flattened faces permitting lowering of the platen at intervals, and means for continuously operating said cams.
18. The combination, in a machine for bottoming vials, of a rotating blank support, supporting means for the same, a substantially horizontal movable platen upon which said supporting means rest, springs tending to lower said platen, and cams in engagement with the under side of the platen, said cams serving to hold the platen normally in the elevated position, and provided with flattened faces permitting lowering of the platen by the action of the springs at intervals, and means for operating said cams continuously.
19. The combination, in a machine for bottoming vials, of rotating blank carriers, supporting means for the same, a substantially horizontal movable platen upon which said supporting means rest, rollers carried by said supporting means and engaging the platen, springs tending to lower said platen, cams in engagement with the platen, said cams serving normally to hold the platen in the elevated position and provided with flattened faces permitting lowering of the platen at intervals, means for rotating said cams, and means for adjusting the supporting means for the blank carriers.
20. In a vial forming machine, the combination of blank supports, means for rotating the same, means for reciprocating said supports in a longitudinal direction with respect to the axis of rotation, means for simultaneously heating the blank, a bottom forming device for engagement with the separate sections when the blank is severed, and means for moving said bottom forming device into alinement with the sections.
21. In a vial forming machine, the combination of separated blank supports, means for rotating the same, means for reciprocating said blank supports in a longitudinal direction with respect to the axis of rotation, means for simultaneously heating the blank, a bottom forming device for engagement with the separate sections when the blank is severed, means for moving said bottom forming device into operative position with respect to said sections, and cushion means for the bottom forming elements.
22. In a machine for bottoming vials, the combination of a plurality of sets of rotatable vial blank supports arranged to engage the peripheral portions of the blank, means for heating the mid-portion of the blank, and means for longitudinally moving said sets of vial blank supports together with the portions of the blank away from each other as the blank is heated to effect separation of the same into two sections.
23. In a machine for bottoming vials, the combination of a plurality of sets of rotatable rollers forming vial blank supports, other rollers for engaging the blanks to hold them on the blank supporting rollers, means for rotating the rollers of each set, and means for effecting the longitudinal movement of said sets of rollers with respect to each other to separate the blanks.
24. In a machine for bottoming vials, the combination of a plurality of separate and independent sets of rollers forming a vial blank support, an additional roller for each set arranged to engage the blank and hold it in contact with the other rollers, a stop for each end of the blank, and means for moving said sets of rollers in a line parallel to the axis of the blank.
25. In a machine for bottoming vials, the combination of two sets of rotating roller supports, a top roller for each set, and means for effecting lateral movement of said sets of rollers.
26. The combination, in a machine for bottoming vials, of rotating blank supports, a stop for each end of the blank, means for directing flame jets to heat the central portion of the blank, means for moving both blank supports longitudinally with respect to the axis of the blank.

- to the axis of the blank, the movement in one direction stretching said blank and separating the same into two sections as it is heated, and a yieldable die for axial alinement with 5 said sections.
27. The combination, in a machine for bottoming vials, of a rotating blank support, means for directing flame jets to heat the central portion of the blank, means for moving the blank supports longitudinally with respect to the axis of the blank, the movement in one direction stretching said blank and separating the same into two sections as it is heated, a die for axial alinement with 10 15 said sections, a pair of yieldable bottoming members carried by said die for engagement with the sections upon the return movement of the blank supports, and means for moving said die.
28. The combination, in a machine for bottoming vials, of independent sets of rotating blank supports, arranged to grasp the body of the blank, laterally moving 20
- members supporting the several sets, a stop for each end of the blank and means for moving said members toward and from each other.
29. In a machine for bottoming vials, the combination of a plurality of sets of rotatable rollers forming vial blank supports, an additional roller for each set arranged to engage the blank and hold it in contact with the other rollers, means for rotating the rollers of each set, and means for effecting the longitudinal movement of each set of rollers with respect to each other to separate the blanks.

In testimony whereof, we have signed our names to this specification, in the presence of two subscribing witnesses.

WILLIAM DAYTON FREDRICK.
WARREN E. GLASPEY.
